E. A. DE CAMP, OF ST. LOUIS, MISSOURI.

Letters Patent No. 74,753, dated February 25, 1868; antedated January 24, 1868.

IMPROVEMENT IN COAL-STOVES.

The Schedule referred to in these Letters Patent and making part of the same.

TO ALL WHOM IT MAY CONCERN:

Be it known that I, E. A. DE CAMP, of the city and county of St. Louis, and State of Missouri, have invented a new and useful Improvement in Stoves; and I do hereby declare that the following is a full and clear description thereof, reference being had to the accompanying drawings, and to the letters of reference marked thereon.

This invention consists in an improvement upon the common egg-shaped coal-burning stoves, the said improvement being the addition to the said stove of an annular cooking-top, thus adapting the best-known soft-coal-burning stove to culinary purposes.

To enable those skilled in the art to make and use my improved stove, I will proceed to describe its construction and operation.

Figure 1 of the drawings is an elevation of the improved stove.

Figure 2 is a top plan of it.

Figure 3 is a central sectional elevation.

Figure 4 is a bottom plan of the heat-distributing disk.

The base of the stove, A, may be the common egg-shaped stove, used for heating purposes only up to the present time, and found to be the best-adapted to the use of bituminous coals. The top of this part of the stove is covered with a convex diaphragm, B, perforated with openings b, for the escape of the smoke and hot gases into the annular chamber C, formed between the annular disks C¹ and C². The lower one of these disks, C¹, should be inclined upward from its centre to the periphery, so as to contract the section of the chamber C at its periphery in such a manner as to leave no dead-atmosphere in the angle formed by the connection of the disk C with a vertical wall. The disk C², which forms the top plate of the stove, should have a horizontal flat top surface, and be perforated with openings, c, for the reception of cooking-vessels. A central opening, c¹, is for the smoke-pipe P. Each of the openings c is provided with a covering-plate, c², secured by means of a chain, c³, with the pipe P, and a hook, p, is attached to the said pipe at the end of each chain, for the purpose of hanging up the said covers out of the way when not in use. This device of chains and hooks is of peculiar utility, as this stove is especially designed and adapted for use as a deck-stove on emigrant and other vessels. A radiating diaphragm, C³, convex on its lower surface, and inclined upward from its centre to its periphery, is interposed between the disks C¹ and C², as clearly shown in figs. 3 and 4. The periphery of this diaphragm where it joins the disk C² falls in a circular line, bisecting the openings c; or nearly so, therefore semicircular notches, c⁴, are cut in it, so as to fully uncover the bottoms of the openings c, as is represented in fig. 4. The openings b, in the diaphragm B, are placed directly under the salient wings c⁴ of the diaphragm C³ between the openings c, as is also clearly shown in fig. 4.

This arrangement compels the smoke and hot gases arising from the burning fuel in A to pass directly under each of the cooking-places c, and in so contracted a space as to utilize the greatest possible amount of caloric. The semicircular notches c⁴ cut in the periphery of diaphragm C³ afford openings between C² and C³ for the passage of the smoke into the smoke-chamber C⁴, shown in fig. 4, and from thence it passes up into the pipe P. The tortuous passage presented for the exit of the smoke through the chambers C and C⁴, and the interposition of the diaphragms B and C³, which while in use become heated, render this arrangement of a stove nearly a smoke-consumer, and a great saving of fuel is thereby effected.

Having described my invention, what I claim, is—

1. The annular cooking-top C¹ C², in combination with the stove A, substantially as described and set forth.
2. I claim the diaphragms B and C³, when combined with the disks C¹ and C², substantially as described and set forth.

E. A. DE CAMP.
